(57) **CLAIM**

I claim the ornamental design for a stackable container, as shown and described.

DESCRIPTION

FIG. 1 is an exploded top perspective view of a stackable container, showing my new design;

FIG. 2 is a bottom perspective view thereof;

FIG. 3 is a front elevational view thereof, the rear elevational view, right-side elevational view, and left-side elevational view all being a mirror image thereof;

FIG. 4 is a top plan view thereof; and,

FIG. 5 is a bottom plan view thereof.
